UNITED STATES PATENT OFFICE.

JOSEPH B. SHERMAN, OF MERIDEN, CONNECTICUT.

DESIGN FOR A KNIFE OR SIMILAR ARTICLE.

Application filed September 12, 1923. Serial No. 7,184. Term of patent 7 years.

To all whom it may concern:

Be it known that I, JOSEPH B. SHERMAN, a citizen of the United States, residing at Meriden, in the county of New Haven and State of Connecticut, have invented a new, original, and ornamental Design for a Knife or Similar Article, of which the following is a specification, reference being had to the accompanying drawing, forming part thereof.

I claim:

The ornamental design for a knife or similar article as shown.

JOSEPH B. SHERMAN.

Witnesses:

EVA SHERMAN,
G. L. HUSSIER,
